No. 639,403.

Patented Dec. 19, 1899.

G. O. H. KLOPP.

COCK.

Application filed Oct. 31, 1898.

(No Model.)

UNITED STATES PATENT OFFICE.

GEORGE ONNO HOMFELD KLOPP, OF LONDON, ENGLAND.

COCK.

SPECIFICATION forming part of Letters Patent No. 639,403, dated December 19, 1899.

Application filed October 31, 1898. Serial No. 695,071. (No model.)

To all whom it may concern:

Be it known that I, GEORGE ONNO HOMFELD KLOPP, a subject of the Queen of Great Britain and Ireland, residing at Chelsea, 5 London, England, have invented Improvements in Cocks or Taps, of which the following is a specification.

Cocks or taps (hereinafter called "taps") have heretofore been constructed with ball-10 valves working against an annular seat of elastic material, such as india-rubber, and opened by an endwise-movable spindle; but all such previous constructions, so far as I am aware, possess many serious practical disadvantages, being costly to construct, difficult to 15 maintain in a fluid-tight condition, liable to distortion and rapid wear of the valve-seat, and difficult to repair while under pressure.

This invention relates to an improved construction of tap that is very simple and cheap to construct and very efficient and durable in use.

In the accompanying drawings, Figure 1 shows in central vertical section a tap constructed according to my invention, the tap being shown open. Fig. 2 shows the same tap when closed. Figs. 3, 4, and 5 represent a plan, section, and front view, respectively, of a clamp-ring, hereinafter referred to.

The tap, which is of the well-known valve bib-tap pattern, is formed with two chambers or passages—viz., an outlet-chamber A and an inlet-chamber B. In the inlet-chamber B, directly below a spindle C and in the open space B', I place a ball D, made of some hard non-compressible or not easily compressible material—such, for example, as metal. I find in practice that a hollow metal ball capable of floating in water or other fluid may advantageously be used. This ball D when the tap is open lies in the cup of the screw-cap E, which forms the lower portion of the space B', in which the metal ball works. I use a screw cup-shaped cap, as in some forms of tap at 40 present in use, as it enables me to remove the ball easily when necessary.

In casting the tap an aperture is left in the diaphragm between the chambers or passages A and B, and on the upper side of a shoulder 45 surrounding this aperture that is in the chamber A there is placed an india-rubber or other suitable ring or washer F, that serves

as a seat for the ball D. The ring or washer F, which is inserted through the chamber A, is secured in position by a loose clamp-ring 55 or distance-piece G, having an aperture G' on one side to permit of the flow of liquid through the tap. The clamp-ring is also inserted through the upper or outlet chamber A and is held in position laterally by a key H in the 60 outer casting, which fits into a keyway H' in the clamp-ring. (See Fig. 3.) When the stuffing-box L, hereinafter referred to, is screwed down into the outlet-chamber A, the clamp-ring G is forced downward thereby and held 65 perpendicularly, thus firmly retaining the washer or ring F in position, and as the clamp-ring is prevented from rotating the screwing in of the stuffing-box L will not produce any twisting or distortion of the seat-ring F. This 70 method of introducing and securing the seating is a most important feature of my invention, as I have found in practice that a ring inserted and secured by projections below the aperture and between the two chambers becomes dislodged or forced out of shape 75 under high pressure, thus causing an escape of fluid. In the outlet chamber or passage A, I place a spindle C, as in former constructions of taps. The spindle C is attached to the 80 screw-spindle I and is forced down through the aperture between the two chambers and raised by means of the screw when the handle J at the top is rotated. In order to minimize friction against the ball D, I may attach to 85 the face of the spindle C a small conveniently-shaped pad of suitable material, such as india-rubber. At a suitable distance below the crutch or handle J on the screw-spindle I there is placed or formed a ring K to limit 90 the distance that the spindle can be screwed down. An ordinary stuffing-box L L', with stuffing M, is screwed into the top of the tap, as shown, to secure the screw-spindle I and the clamp-ring G in position and to prevent 95 leakage. The ball D is made large enough to prevent its passing through the aperture formed in the tap between the two chambers A and B, so that the ring or washer F can be replaced by a new one without having to cut 100 off the supply of water to the tap, the ball at this time seating itself against the metal edge of the aperture.

Upon water or other liquid being introduced

to the chamber or passage B under pressure the ball D rises from the cup in the screw-cap E into the space B' toward the aperture between the two chambers and is there kept in 5 position against the rubber or other ring or seat F by the pressure of the liquid and in this way closes the tap.

To open the tap, the spindle C is screwed down, so as to force the ball toward the cup 10 in the screw-cap E, and thereby open the aperture between the chambers and permit the water or other liquid to flow through the tap.

As will be seen, the improved cock is very 15 simple in construction, the elastic valve-seat F is held firmly in place without liability of its being distorted by the means employed for fixing it in place or of being dislodged or forced out of shape by liquid under high pressure in contact therewith, and the said seat 20 can be readily inserted and fixed in place or removed while liquid under pressure is within the chamber B.

What I claim is—

1. A cock or tap comprising a body formed 25 with an inlet - chamber having a discharge-aperture, a ball-valve located in the inlet-chamber and of such a size that it cannot pass through the discharge-aperture, a ring or washer held in position by a non-rotatable 30 clamp-ring within the said aperture so as to serve as a valve-seat and means whereby the said ball can be forced from its seat against the pressure of the fluid, substantially as described.

35 2. A cock or tap comprising a body formed with an inlet - chamber having a discharge-aperture, a ball-valve located in the inlet-

chamber and of such a size that it cannot pass through the discharge - aperture, an elastic ring or washer held in position by a non-rotatable clamp-ring within the said aperture 40 so as to serve as a valve - seat and means whereby the said ball can be forced from its seat against the pressure of the fluid, substantially as described.

45 3. A cock or tap comprising a body formed with an inlet - chamber having a discharge-aperture, an elastic washer held upon the discharge side of said aperture by a non-rotatable clamp-ring, said elastic washer projecting beyond the edges of said aperture and serving as a valve-seat for a ball-valve within said inlet-chamber, substantially as described.

4. In a cock or tap the combination of a 55 body formed with inlet and outlet chambers, a diaphragm separating said chambers and having an aperture therethrough, a ball-valve located within said inlet - chamber and of such a size that it cannot pass through said 60 aperture, an elastic washer within said aperture, a clamp-ring pressing against said elastic washer and formed with a keyway, a key on said body engaging said keyway and holding said clamp-ring immovable and a stuffing- 65 box adapted to force down and hold said non-rotatable clamp - ring, substantially as described.

Signed at 2 Pope's Head alley, Cornhill, in the city of London, this 7th day of July, 1898. 70

GEORGE ONNO HOMFELD KLOPP.
